US0D1078532S

(12) **United States Design Patent** (10) **Patent No.:** **US D1,078,532 S**
(45) **Date of Patent:** **** Jun. 10, 2025**

(54) **WATCH STRAP CONNECTOR**

(71) Applicant: **Fuyun Wang**, Yiyang (CN)

(72) Inventor: **Fuyun Wang**, Yiyang (CN)

(**) Term: **15 Years**

(21) Appl. No.: **29/961,255**

(22) Filed: **Sep. 5, 2024**

(51) **LOC (15) Cl.** **11-01**

(52) **U.S. Cl.**

USPC **D11/94**; D10/38

(58) **Field of Classification Search**

USPC D11/86, 87, 94, 200, 201, 220; D10/30, D10/32, 38; D14/344; D8/382

(57) **CLAIM**

The ornamental design for a watch strap connector, as shown and described.

DESCRIPTION

FIG. 1 is a front perspective view of a watch strap connector, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view.

The broken lines in the drawings illustrate the portions of the watch strap connector, which form no part of the claimed design.

1 Claim, 8 Drawing Sheets
